UNITED STATES PATENT OFFICE.

JOHN W. JOHNSON, OF WAYCROSS, GEORGIA.

WALL CONSTRUCTION.

Application filed November 2, 1923. Serial No. 672,393.

To all whom it may concern:

Be it known that I, JOHN W. JOHNSON, a citizen of the United States, residing at Waycross, in the county of Ware and State of Georgia, have invented certain new and useful Improvements in Wall Constructions, of which the following is a specification.

This invention relates generally to buildings and has more particular reference to the wall construction thereof, the primary object of the invention residing in the manner of constructing walls wherein buildings may be constructed at a cost considerably less than has been possible up to the present time.

In carrying out this invention it is my purpose to provide a wall construction wherein the major portion thereof comprises logs of wood or analogous material, preferably cut directly from trees, the different longitudinal rows of timbers being supported upon and between the next under row and jointed thereto by a plastic material, preferably mortar, tie members being provided between the opposite ends of certain of the rows of timbers for co-operating with the hardened mortar for preventing any movement of the timbers with respect to each other.

It is also my purpose to provide a wall construction, wherein the major portion thereof consists of cheap blocks of wood such as lengths of logs or timbers, and whereby a suitable plaster and stucco may be placed upon the inner and outer faces of the walls for giving to the building the appearance of a concrete construction, and for providing a structure wherein the same will be as strong and durable as a concrete building.

It is therefore an object of this invention to provide a wall construction wherein the same may be set up without the employment of expensive and complicated concrete wall forms, and wherein the same will be as wholly fire and moisture proof as the expensive full concrete walls.

With the above recited objects in view and others that will appear as the nature of the invention is better understood, the same comprises the novel wall construction hereinafter more fully described, shown in the accompanying drawing and claimed.

In the drawing wherein there is shown the most practical embodiment of the invention with which I am at the present time familiar and wherein like reference charac-

ters indicate corresponding parts throughout the several views.

Figure 1 is a sectional view through a pair of partly completed, interconnected building walls constructed in accordance with this invention, 60

Figure 2 is a side elevational view thereof, and 65

Figure 3 is a fragmentary, vertical, sectional view of a complete building wall constructed in accordance with this invention. 65

Now having particular reference to the drawing, wherein there is shown a pair of inter-connected building walls constructed 70 after the most preferable embodiment of the present invention, A and B designate generally said walls.

In carrying out this invention, longitudinal rows of relatively short logs or timbers 5 are arranged in adjacent spaced relation and in a direction transverse to the length of the respective wall as clearly shown in Figure 1. It is preferable that the diameter of the elements 5 be not more than 75 four or five inches. 80

Adjacent ends of alternate rows of timbers 5 of the walls A and B, overlie each other for providing an inter-locking joint between the meeting ends of the walls, 85 Figures 1 and 2, it being of course understood that the remaining alternate rows of logs or timbers must terminate short of the other rows a distance of substantially the length of the timbers, Figure 2. 90

Between superposed rows of timbers is a filling of mortar 6, which while in its plastic state finds its way into the spaces between the logs for securely connecting the rows of logs together as well as inter-connecting the timbers of one row with those of the other rows. From a consideration of Figure 2 it will be obvious that the logs or timbers of one row are positioned between the logs or timbers of the next under row, for consequently preventing any rolling of the logs before the mortar has properly set. 95

The amount of mortar placed between the rows must not be such as to allow the same to reach the opposite ends of the logs but should terminate within the logs for providing horizontal and vertical channels whereby stucco or the like and plaster 7 and 8 respectively, may be properly applied to the opposite faces of the walls. 100 105

During the construction of the walls, spaced pairs of longitudinal bonding strips 110

9 are positioned upon alternating rows of logs or timbers 5 of the walls A, B for not only assisting in retaining the timbers in proper position but for also providing a means whereby the logs may be supported in a true horizontal alinement.

Alternate pairs of binding strips 9 carry adjacent their opposite ends the wires 10 that extend considerably outwardly from the ends of the binding strips. There the wires are suitably secured to the under side of the body strips and in actual practice the projecting ends of the tie wires are bent upwardly after which the bending strips may be laid. After its walls have been built up several more rows these tie wires are then bent inwardly and secured, preferably through the medium of walls 11 passing through eyes 12 formed by looping the wire, to the next parallel rows of binding strips 9.

During the construction of the building employing the present type wall formation vertical planks 13 and 14 respectively, are arranged at opposite sides of the wall corners for providing a guide or gauge for the walls and for overcoming the necessity of employing plumb bobs, etc., for this purpose, and also for supporting the plastic material at its most delicate portions, namely, corners and ends of walls during the course of construction.

As shown in Figure 3 sleepers 15 are positioned upon the upper ends of the walls for supporting the usual roof rafters 16.

It will thus be seen that I have provided a highly durable, water-proof, fire-proof and inexpensive wall construction for buildings and one that may be set up in relatively short time and this without requiring highly skilled workmen.

I have herein shown and described the most practical embodiment of the invention with which I am at the present time familiar, it being nevertheless understood that minor changes may be made within the invention without departing from the spirit and scope of the appended claim.

Having thus described my invention, what I claim as new and desire to secure by Letters Patent is:

In a wall construction, a plurality of superposed horizontal rows of comparatively short logs extending transversely of the length of the wall, said logs being substantially uniform in diameter and the logs of one row being disposed in staggered relation with respect to those of the other row, all of said logs being spaced apart to permit a cement filler or binding material to be placed therebetween for maintaining them in their proper relative positions, bonding and leveling strips arranged between alternating rows of the logs, and tie wires for connecting the end logs and leveling strips together.

In testimony whereof I affix my signature.

J. W. JOHNSON.
